UNITED STATES PATENT OFFICE

150,231

DESIGN FOR A COMB

Crofton C. Holden, Leominster, Mass., assignor to Tilton & Cook Co., Leominster, Mass., a corporation of Massachusetts

Application May 22, 1946, Serial No. 129,976

Term of patent 14 years

(Cl. D86—8)

To all whom it may concern:

Be it known that I, Crofton C. Holden, a subject of King of Great Britain, residing at Leominster, in the county of Worcester and Commonwealth of Massachusetts, have invented a new, original, and ornamental Design for Combs, of which the following is a specification, reference being had to the accompanying drawings, forming a part thereof.

In the accompanying drawings Fig. 1 is a perspective view of a comb showing my new design. The other side of the comb is substantially like that shown.

I claim:

The ornamental design for a comb, substantially as shown and described.

CROFTON C. HOLDEN.
